UNITED STATES PATENT OFFICE.

HENRY G. LANGE, OF CHICAGO, ILLINOIS, ASSIGNOR TO CHARLES E. STRONG,
OF SAME PLACE.

STEREOTYPE-CASTING MACHINE.

SPECIFICATION forming part of Letters Patent No. 443,662, dated December 30, 1890.

Application filed September 8, 1890. Serial No. 364,241. (No model.)

To all whom it may concern:

Be it known that I, HENRY G. LANGE, a citizen of the United States, residing at Chicago, county of Cook, and State of Illinois, have invented certain new and useful Improvements in a Stereotype-Casting Machine, which are fully set forth in the following specification, reference being had to the accompanying drawings, forming a part thereof.

10 The purpose of this invention is to provide an improved means for automatically and with uniformity clamping the cover onto the matrix-bed of a stereotype-casting machine preparatory to running in the metal, and for automatically releasing the cover from the binding of such clamping device when the casting is about to be removed.

Figure 1 is a side elevation of the stereotype-casting machine of a familiar construction, except as to my new clamping devices, which are shown thereon, the bed being in upright position, as when the material is being poured in during casting and the cover being therefore shown clamped to the bed. Fig. 2

20 is a similar side elevation showing the bed horizontal, as when the cast is completed ready to be removed, the cover being shown released from the clamp, but still closed in full lines, but in open position in dotted lines. Fig. 3 is a sectional detail inner side elevation of one of the clamping-cams, showing one of the trunnions on which the bed swings; and showing the cross-shaft of the frame, which acts as a stop for the cam, said trunnion and cross-shaft being in section at a vertical plane alongside the bed. Fig. 4 is an axial section through the bed-trunnion and its bearing. Fig. 5 is an end elevation looking in the direction indicated by the arrow 5

30 on Fig. 2.

A is the frame in which the bed swings. It comprises, with other familiar parts, the upright standards A', which afford bearings for the bed-trunnions.

40 B is the matrix-bed.

C is the cover or box, the same being pivoted to the bed at c at one end of the latter.

C' is the mouth or funnel at which the metal is poured in at the end opposite the hinge or pivot of the cover to the bed.

50 The machine has the usual devices for lock-

ing the bed in horizontal position and for locking the cover in open position when the bed is horizontal.

D D are the clamping-cams. They are hung 55 on the bed-trunnions B' B', respectively, between the bed and the bearing-standards A', as seen in Fig. 4.

D' is a cam groove or slot in the upper arm of the pivoted cam D, having its outer boundary eccentric to the axis of the trunnions.

C² is a stud, which projects laterally from the edge of the cover C and enters the cam-slot D' at one end of the slot as the bed swings up from horizontal position. The outer boundary of the slot at the end at which the stud thus enters is farthest from the axis of the bed, so that as the bed continues to swing upward toward its vertical position the stud is drawn in toward the axis of the bed, thereby drawing the cover down toward the bed, and at the limit of the upward swinging movement of the latter, when the stud has reached the limit of the cam-slot, the cover is by the engagement of the stud in the eccentric-slot clamped positively and tightly onto the bed, this position being reached, as stated, when the bed is at its proper upright position adapted for receiving the melted metal, which is then poured in at the funnel end in 80 the customary manner.

In order that the box may be swung by the hand of the operator slightly from the vertical position to a position a little inclined, as it is sometimes necessary and always desirable to be able to swing it when pouring the metal, and that this variation of position may be effected without relaxing the clamping to any degree, the cams D are not made rigid, as they otherwise might be, with the standards, but are shown hung on the trunnions and have the lower arm D² extended down to the cross shaft or bar E and are provided at their lower end with a slot D³, through which said cross-bar passes, said slot being in the 95 arc of a circle about the axis of the bed and permitting the cams to swing on the trunnions a distance corresponding to the length of that arc slot, the cams being stopped at the limit of such swinging movement by the 100 cross-shaft E in the slots D³. It will be understood that the first pressure experienced

by the cam from the stud C^2 as it enters the eccentric groove in the upper arm of the cam will tend to swing the cam on the trunnion, and said pressure will eventually so swing 5 the cam until it is stopped by the end of the slot reaching the shaft E , that thereafter during the movement of the bed toward the vertical position the cam is unchangeable in position as if fixed to the standard, and that 10 when the stud C^2 has reached the end of the eccentric cam-slot and the cover is bound tightly on the bed the frictional engagement of the stud in the slot will be sufficiently positive so that the bed and cover and the cams 15 will all swing together to the extent of the arc slot D^3 in the lower arm of the cam. This device removes all necessity for the usual removable clamping-jaws or clamping-bolts and serves to secure the bed and cover and obviates all necessity for special attention of 20 the operator to that feature in working with the machine, the clamping being automatically performed in the act of bringing the box to the vertical position necessary in order 25 to charge it with the metal. In like manner the clamping is undone and the cover released from the bed automatically by the movement of the bed, which brings it into the horizontal position necessary for removing 30 the casting.

For each of the cams D a spring-bar F is provided, which is secured at one end to the frame and at the other end engages the cam, tending to resist the swinging of the latter in 35 the direction in which it is forced by the movement of the bed toward vertical position. As illustrated, the engagement of the springs with the cams is effected by a lug or projection d on each of the cams, behind which the 40 end of the spring is lodged. These springs thus act as buffers to prevent the jar which might otherwise be attendant upon too sudden stoppage of the bed at the limit of its movement. They also assist in starting the 45 bed when it is to be swung away from that position. By causing the buffer-springs to act against the cams instead of directly against the bed they are made to serve the purpose of holding the cams in engagement 50 with the studs on the bed, so that the clamping is not relaxed during the slight movement of the bed which is permitted by the slots D^3 .

I claim—

55 1. In a stereotype-casting machine, in combination with the frame and the casting-box journaled therein, cams D , adjacent to the trunnion-bearings of the box and having the cam-grooves whose operating boundary is 60 eccentric to the axis of the box, the cover of the box being provided with studs projecting laterally therefrom in position to enter and move in the cam-grooves as the box is swung from horizontal to vertical position, whereby

the movement of the box from horizontal to 55 vertical position causes the cams to clamp the cover onto the bed and the reverse movement releases the cover from such clamping, substantially as set forth.

2. In a stereotype-casting machine, in combination with the frame, the casting-box supported in bearings thereon and adapted to swing in such bearings from horizontal to vertical position, cams D , pivoted about the axis of such box and adapted to swing about said 70 axis, and stopped on the frame at the limits of a short swinging movement, said cams having the grooves D' , whose operating boundary is eccentric to the axis of the box, the cover of the box being provided with studs to engage and move in said cam-grooves, whereby the box and cover and cams are clamped together during the movement of the box toward vertical position, and thus clamped together have short range of oscillation near 80 the vertical position, substantially as set forth.

3. In combination with the frame and the casting-box journaled in horizontal bearings thereon and adapted to oscillate between horizontal and vertical position about said bearing, cams D , pivoted about the axis of the box, having at their upper ends the eccentrically-bounded grooves D' and at their lower end the slots D^3 , the box having studs which enter the grooves while the box is swinging 95 from horizontal to vertical position, and the shaft or bar E of the frame extending through the slots D^3 to serve as a stop for the swinging movement of the cams, all substantially as set forth.

4. In combination with the cam and the casting-box journaled in horizontal bearings thereon and adapted to oscillate between horizontal and vertical position about said bearings, cams D , pivoted about the axis of the 105 box, having at their upper ends the eccentric grooves D' and at their lower ends the slots D^3 , the box having studs which enter the eccentric grooves while the box is swinging from horizontal to vertical position, and the shaft or bar E of the frame extending 110 through the slots D^3 to serve as a stop for the swinging movement of the cams, and springs reacting between the frame and the cams, respectively, and tending to resist the swinging 115 of the latter in the direction in which the movement of the box away from horizontal position tends to force them, substantially as set forth.

In testimony whereof I have hereunto set 120 my hand, in the presence of two witnesses, at Chicago, Illinois, this 3d day of September, 1890.

HENRY G. LANGE.
